UNITED STATES PATENT OFFICE

WILLIAM E. JENSEN, OF CHICAGO, ILLINOIS, ASSIGNOR, BY MESNE ASSIGNMENTS, TO
F. W. NORTON, OF OAK PARK, ILLINOIS

CAN OPENER

Application filed January 31, 1931. Serial No. 512,625.

My invention relates to can openers. It relates more in particular to the type of can opener in which the entire top of the can is removed by cutting action so that the contents of the can may be removed.

The principal object of the invention is the provision of an improved can opener.

Another object is the provision of a can opener which adjusts itself automatically to peculiarities in the shapes of various types of cans.

Another object is the provision of a can opener, which is economical to manufacture and which will have a long life.

Another object is the provision of a can opener in which the can opener may serve as a handle for lifting the can and dumping the contents thereof.

Another object is the provision of means for preventing fine particles of metal from dropping into the food.

Another object is the provision of means for preventing the top of the can from dropping into the body thereof.

Other objects and features of the invention will be apparent from a consideration of the following detailed description taken with the accompanying detailed drawings, wherein

Fig. 1 is a perspective view showing the can opener and the manner in which it is attached to a can,

Fig. 2 is a fragmentary side elevational view thereof,

Fig. 3 is an enlarged vertical sectional view,

Fig. 4 is a side elevational view of the can opener, the view being from the opposite side as that from which Fig. 2 is taken,

Fig. 5 is a perspective view of a removable magnet for preventing metal particles from dropping into the can,

Fig. 6 shows the can opener used for pouring the contents of the can,

Figs. 7 and 8 represent modified magnet means for preventing particles of metal from dropping into the can,

Fig. 9 shows a modified construction of the can opener,

Fig. 10 is a sectional view thereof taken along the line 10—10 of Fig. 9 and Fig. 11

is a perspective view of a magnet as shown in the modified form.

In general the can opener comprises a knife which engages into the top of the can to cut the same and a feed wheel which engages under the bead at the top edge of the can to advance the can opener around the top of the can so that the knife cuts around the edge of the top. The feed wheel is moved into contact with the bead by lever action, and the feed wheel and knife cooperate to compensate for irregularities in the bead, or varying sizes of beads from one can to another. A magnet is provided with one pole adjacent the knife to pick up small particles of metal which are cut away from the can and become separated therefrom as the can is opened. A body portion to which the cutting and feeding mechanism is attached is provided and such body portion has guide means for governing the position which the can opener takes when applied to the can.

Referring now to the drawings,

The can opener comprises a body portion 16 in the form of a flat piece of metal having top guide members 17 and 18, which normally ride over the top edge of the can when the opener is attached thereto, and a bottom guide member 19, which constitutes a flange at the bottom of the body member and engages along the side of the can (Fig. 3). The body portion carries a knife 21 secured thereto by rivets 22 and separated from the body portion by a liner 23. This knife, formed of suitable steel, has a cutting edge 21a disposed at an angle to facilitate cutting and also arranged so that the knife may extend a very slight distance, or a comparatively great distance below the normal plane of the top of the can and fully satisfactory cutting action take place. It is obvious that if the knife moves around the top of the can in the direction shown by the arrow in Fig. 4, the top cover 24 will be excised from the can 26.

If Fig. 3 will be examined it will be seen that the top 24 is cut at the very inside edge thereof adjacent the bead 27. The feeding means for moving the can opener around the top of the can is made to engage the lower outside portion of the bead 27 and operate 100

in such a way as to move the can opener about the top of the can.

As to the feeding means, this will be described in connection with the means for attaching the can opener to the can. This comprises a bell crank lever 28 pivoted to the body member by pivot pin 29, the bell crank lever having an elongated pivot opening 31. One arm of the bell crank constitutes the handle 32 and the other arm of the bell crank constitutes a feed wheel carrying mechanism 33.

The portion 33 has journaled therein a stub shaft 34 to the inside of which a hardened steel feed wheel 36 is secured having teeth 37 adapted to engage under the bead 27. The shaft 34 carries a sleeve 38 just clearing the side edges of an arcuate slot 39. A washer 41 engaging the member 33 on one side thereof, and the feed wheel 36 engaging the body portion at the opposite side holds the feed portion assembled. The washer 41 is held by the feeding handle 42, the handle being secured to the shaft 34 in any suitable way.

Before referring more completely to the operation of the device, it may be said that by the operation of the feeding handle 42 and the handle 32, the can opener is fitted to the top of a can and moved around the can to open the same. In the cutting action incidental to the opening, fine shreds and slivers of the metal may be cut from the body of the can and it is desired, if possible, to prevent these particles from falling into the food. I accomplish this by means of a horse shoe magnet 43 having pole pieces 44 and 46. The pole piece 44 is made relatively narrow and is adapted to fit into a cut-away portion of the liner 23. The pole piece 46 then is close to but out of contact with the knife 21 so that it will pick up substantially all of the particles cut from the can, but will not lose its magnetism by reason of contact with the knife or other portions of the opener. Since the magnet is removable, it can be produced separately from the can opener with a full charge of magnetism and then merely fitted into position where it is held frictionally. As Fig. 3 shows, a slight bend is provided in the pole piece 44, causing the same to fit snugly between the body portion and knife 21. Should a magnet lose its power, it can be removed from the opener and another magnet supplied in its place.

Figs. 7 and 8 show modifications in which a magnet 143 is provided having pole pieces 144 and 146. In this magnet the pole piece 144 serves as a liner between the body portion of the can opener and the blade thereof and is held permanently in place, it being assembled with the can opener by means of the rivets 22.

In the operation of the can opener, the handle 32 is grasped in the left hand and with

the can opener in the position shown in Fig. 1 the body portion is turned with respect to the handle as far as possible in a counter clockwise direction. In this position the handle projects up somewhat vertically, the angle to the vertical being roughly about thirty degrees with the particular dimensions, etc. employed by me. The can opener is then placed against the can with the guide members 17 and 18 extending over the top edge and the flange 19 along the outside of the cylindrical portion of the can body. In this position the knife rests lightly on the top 24 and the feed wheel 36 is slightly below the outside of the bead 27. The butterfly handle 42 is then grasped with the right hand and the handle 32 with the left hand. The butterfly handle 42 is then turned in a clockwise direction and the handle 32 lowered to substantially a horizontal position. This moves the knife 21 and the feed wheel 36 closer to each other so that they overlap, the knife forcing its way through the top 24 and the feed wheel engaging snugly against the edge of the bead 27. Continued movement of the butterfly handle 42 will then have the effect of rotating the feed wheel 36, the teeth 37 engaging the bead 27 and moving the entire can opener about the top of the can. Whether the can moves or the can opener moves will depend on conditions, but they will move relatively to each other until the entire top 24 is excised from the can. Fine particles 43 are picked up by the magnet and when the cover is completely removed it will adhere sufficiently to the magnet to prevent its dropping into the can, whence it is sometimes difficult to extract.

I make use of the resilient character of the top 24 to hold the feed wheel against the bead at the top of the can, and due to the shape of the knife an automatic adjustment is obtained for irregularities or non-uniformity in the shape and size of the bead. I may provide additional means to secure this result, however, and Figs. 9 to 11 show one manner in which the additional means can be built into a can opener as shown in the main figures. Here a spring 146, inserted into the body portion 116, engages against the sleeve 138. Since vertical movement of the entire handle assembly is permitted on account of the loose pivot 129, when the feed wheel 136 engages the bead and meets with some resistance, tending to move it downwardly, the sleeve 138 will engage the spring 146, thereby depressing the spring 146 slightly and maintaining at all times while the feed wheel is in engagement with the bead, a slight resilient pressure of the feed wheel against such bead. Not only does this cause more positive action but compensates for irregularities and non-uniformities as described in connection with the main figure. As has been said, however, substantially this same result is obtained.

ble by depending upon the resilient character of the top 24 to maintain this resilient yielding pressure of the feed wheel 36 against the bead.

5 The modified form also shows a different style of magnet 243, in which the pole piece 244 fits entirely around the body portion 116 and between the rivets 122. The pole piece 246 in this form fits down somewhat closer to 10 the knife 121.

One of the advantages of the present style of can opener is illustrated in Fig. 6. This shows the manner in which the contents of the can may be poured by grasping the handle 32.

What I claim as new and desire to protect by Letters Patent of the United States is:—

1. In a can opener, a body portion, a knife carried by the body portion and spaced therefrom, a bell crank lever pivoted to the body portion by a loose pivot and having a feed wheel rotatably secured to one arm of the bell crank lever, the feed wheel engaging under the bead at the top of a can when the bell 25 crank is turned by grasping the other arm thereof, means for shifting the pivoting point of said loose pivot as the bell crank lever is turned and means for turning said feed wheel while in contact with the bead to progress the 30 opener about the top of the can.

2. In a can opener, a body portion having an arcuate slot therein, a knife carried by the body portion at the top thereof, a lever pivoted to the body portion below the slot, a 35 shaft pivoted to the lever and having one end extending through said slot, a feed wheel on one end of said shaft, and grasping means on the other end of the shaft for turning the shaft, and a spring set in the body portion 40 and forming one edge of said slot, the shaft functioning to ride against said spring.

3. In a can opener, a body portion in the form of a flat section of sheet metal, guides at the top thereof adapted to extend over the 45 top bead of the can, a flange at the bottom for spacing the lower portion of the body away from the can, a knife secured to the body in spaced relation thereto and projecting downwardly, a lever pivoted to the body and 50 having a short shaft journaled therein, the shaft extending through an arcuate slot in the body, a feed wheel on the inside end of said shaft, and an operating handle on the opposite outside end of said shaft, said feed 55 wheel adapted to engage the bottom edge of the bead and drive the opener around the can when said operating handle is turned, and a spring disposed adjacent the slot and serving to maintain a resilient pressure 60 against said shaft when the feed wheel is in engagement with said bead.

4. In a can opener, a body member, a knife carried by the body member, means including a feed wheel for moving the knife around the 65 can to excise the top thereof, and a separate

magnet having one pole piece attached to the body member and another pole piece disposed near the knife, but out of contact therewith, for catching particles of metal removed from the can.

70

5. In a can opener, a body portion, a knife secured to the body portion, a handle pivoted to the body portion and having a feed wheel for engaging the head of the can to progress the can opener around the can, and a magnet having one portion disposed between the knife and body portion, and another part disposed near the knife for picking up particles of metal removed from the can.

75

6. In a can opener, a body portion, a knife secured to the body portion, a handle pivoted to the body portion and having a feed wheel for engaging the head of the can to progress the can opener around the can, a bipart liner disposed between the knife and body portion leaving an opening between the knife and body portion in a plane with the liner, and a magnet having one end disposed in said opening and the other end near said knife to pick up metal particles removed from the can.

80

7. In a can opener, a body portion, a knife, means including a feed wheel for moving the knife around the can to excise the top thereof, a magnet, and means for releasably attaching one pole piece of the magnet to the body member, the other pole piece disposed near said knife to pick up metal particles removed from the can.

85

8. In a can opener, a body portion having an arcuate slot therein, a knife carried by the body portion at the top thereof, a lever pivoted to the body portion below the slot on a loose pivot, a shaft pivoted to the lever and having one end extending through said slot, a feed wheel on one end of said shaft, and grasping means on the other end of the shaft for turning the shaft, and a spring set in the body portion and forming one edge of said slot, the shaft functioning to ride against said spring to automatically regulate the position of the feed wheel by reason of said loose pivot.

90

In witness whereof, I hereunto subscribe my name this 27th day of December, 1930.

95

WILLIAM E. JENSEN.
